UNITED STATES PATENT OFFICE.

HENRY MONK, OF CAMBRIDGE, MASSACHUSETTS.

STARCHING-MACHINE.

SPECIFICATION forming part of Letters Patent No. 391,633, dated October 23, 1883.

Application filed October 3, 1887. Serial No. 251,305. (No model.)

To all whom it may concern:

Be it known that I, HENRY MONK, of Cambridge, in the county of Middlesex and State of Massachusetts, a citizen of the United States, 5 have invented a new and useful Improvement in Starching-Machines, of which the following is a full, clear, and exact description, reference being had to the accompanying drawings, forming a part of this specification, in 10 explaining its nature.

The object of the invention is to provide a simple, quick-operating, and cheap machine for starching clothes, and especially the bosoms, collars, and wristbands of shirts; and it 15 comprises various details of construction and organization, all of which will be hereinafter explained.

In the drawings, Figure 1 is a view in front elevation of the machine. Fig. 2 is a side 20 elevation thereof. Fig. 3 is a detail view in vertical section taken from the center of the starching-roll. Fig. 4 illustrates a slight modification.

A is the frame of the machine.

25 B is the starching-roll. It preferably has the peripheral circumferential corrugations b, and it is mounted at the front end of the shaft b', which has two bearings—namely, the front bearing, b², and the rear bearing, b³. The front 30 bearing comprises a block having a hole through which the shaft extends, and is held by suitable vertical guides which permit it to slide vertically, and a spring, b⁴, bears against the block and maintains the roll B in yielding 35 contact with the longitudinally-corrugated surface c of the starching-bed C, or the article of clothing thereon.

The bed C has in its under surface the guide-ways c', which fit the horizontal guides c², 40 upon which the bed is adapted to be moved horizontally. These guides c² are supported by the bracket c³, bolted to the front of the frame A.

The bed C preferably has the corrugated 45 surface c above referred to, and also the extension or section c⁴ in front of the end of the starching-roll, which is generally used as a support for a portion of the garment. The bed is provided with a reciprocating movement 50 by means of the crank-pin d on the wheel D, the connecting-rod d', the lever d'', pivoted at

d³, and the link d⁴, connecting the upper end of the lever with the bed at d⁵. (See Fig. 1.) The crank-pin d is movable toward and from the center of the wheel D in the slot d⁶, formed 55 therein, and is fastened thereto in any desired position, and the end of the connecting-rod d' is secured to the lever d'' by a bolt or pin, d', which is also vertically adjustable in the slot d⁸ in the lever. By these means the throw or 60 extent of travel of the bed C is varied. The bed carries also a holding-bar, E, for holding the article of clothing to be starched on the traveling bed. This holding-bar is hinged at e (see Fig. 1) to the bed C, and has a latch, e', 65 pivoted to the bar E, and engages the catch e² upon the bed C. To the under surface of this bar is a cushion, e³, of india-rubber or other flexible material, which bears upon the upper surface of the article of clothing to be starched. 70 The bed C, preferably, also has a roll, e⁴, held in a deep longitudinal recess formed therein, so that its upper surface shall project slightly above the upper surface, c⁵, of the bed, and when the bed is thus provided with the roll 75 e⁴ it may be used, in conjunction with the cushion e³ to strip or remove surplus starch from the garment, the garment in that event being drawn forward from the holding-bar without raising it from the roll e⁴, and the 80 starch being wiped off the garment by the conjoint action of the cushion and the roll.

The wheel D is mounted upon the shaft d⁹, which has bearings in the frame A and bears a fast and loose pulley.

In operation the article to be starched is laid upon the upper surface of the bed C when at the end of its movement in one direction, the bar E being lifted. Of course only the article to be starched is placed upon the corrugated surface or section of the bed. The other portion or portions are upon the surface c⁵. The bar is then moved down and latched, binding the garment or thing to be starched to the bed. The starch is applied to the roll 95 through a trough, F, held immediately above it, and having a small slit, f, through which the starch is delivered to the roll. The starch enters the trough from a starch-can, G, held upon the table g, and having a nozzle or tube, 100 g', which extends over the trough and is closed in whole or in part by a plug, g², sufficient

starch being permitted to escape from this tube to supply the roll. The machine is then set in operation, and the bed C moves rapidly backward and forward under the roll B, and the roll being held down upon the work by the spring b⁴ is caused to be rotated upon its shaft backward and forward with the corresponding movements of the bed, so that the starch which is fed to its surface is caused to be driven into the garment or article being starched, and is efficiently and uniformly incorporated in it.

In lieu of a cushion, e³, on the holding-bar E there may be used a roll, e⁵, as shown in Fig. 4.

Having thus fully described my invention, I claim and desire to secure by Letters Patent of the United States—

1. In a starching-machine, the combination, with the frame A, of the shaft b', the spring-pressed bearing b² for the forward end of said shaft, the fixed bearing b³ for the rear end of said shaft, the circumferentially-grooved roll B, attached to the front end of said shaft forward of the said spring-pressed bearing, and the reciprocating bed C, arranged beneath said roll outside of said frame and provided with longitudinal corrugations, substantially as set forth.
2. The combination, in a starching-machine, of a roll, B, having a corrugated surface, b,

the bed C, having the corrugated surface c and the extension c', the holding-bar E, and means for automatically imparting to the said bed C a backward-and-forward movement beneath the starching-roll, as and for the purposes described. 35

3. The combination, with the frame A, of the shaft b', the roll B, attached to the forward end of said shaft outside of the said frame, the bed C, also outside of said frame beneath said roll, the rails or guides on which the said bed is mounted, the shaft d', the disk D, attached to the forward end of said shaft outside of said frame, the crank-pin d, adjustably secured to 40 said disk, the lever d', the connecting-rod d', adjustably attached to said lever, and the link d', connecting said lever with said bed, substantially as set forth.

4. The combination, with the roll B and the bed C, having a catch, e², of the roll e⁴, sunk into said bed, but projecting slightly above its surface, the holding-bar E, hinged at one end to said bed and provided with a starch-remover, and a locking-latch at the end of the 55 said bar opposite to its hinged end, substantially as set forth.

HENRY MONK.

In presence of—

F. F. RAYMOND, 2d,
FRED. B. DOLAN.
